BEDSPRING

Morris Tucker, Brooklyn, N. Y.

Application January 21, 1941, Serial No. 375,132

5 Claims. (Cl. 5—192)

This invention relates to bed springs, and more particularly to that type of spring wherein the horizontal mattress supporting surface comprises a metallic fabric formed from links, cables, wire mesh, or the like.

Springs of this type are ordinarily supported between two rigid unyielding end members, but due to the necessity for providing a yielding support along the sides of the spring no such members may be employed thereat. In lieu thereof it has been the practice to provide reinforcing strips at the longitudinal edges of the spring. During normal use, however, said strips and the adjoining edges of the metallic fabric sag appreciably, due to the give of the fabric, and thus cause a bed to become unsightly, noisy and uncomfortable.

To overcome these disadvantages, it has previously been proposed to resiliently urge upwardly the reinforcing strips positioned at the side edges of the metallic fabric by means of any one of several mechanical linkages, usually including a system of levers pivoted on various fixed points in the spring. However, such constructions are relatively expensive and become inoperable in use due to binding of the lever pivot points with rust or dirt, or due to misuse.

In accordance with my invention, therefore, I have provided a unique means for supporting the side edges of a bed spring of the character described, so as to prevent undue sagging thereof, and which overcomes the defects inherent in the complex mechanical linkage systems heretofore employed for this purpose.

Another object of my invention is to provide in a bed spring of the character described sag-preventing means which comprises few and simple parts, and which shall be economical to manufacture, rugged in construction and highly efficient for the purposes set forth.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the claims.

In the accompanying drawing, in which are shown various possible embodiments of this invention,

Fig. 1 is a top plan view of a bed spring constructed in accordance with my invention;

Fig. 2 is an enlarged side elevational view thereof;

Fig. 3 is an enlarged plan view of a corner of said spring;

Fig. 4 is an end view thereof;

Fig. 5 is an enlarged fragmentary perspective view illustrating the novel means employed to prevent sagging of the longitudinal edges of the bed spring; and

Fig. 6 is a fragmentary side view of a modified form of my invention.

In general, I carry out my invention by suspending or hanging each end of a longitudinal rigid reinforcing member, attached to a side of the metallic fabric, on a spring which depends from a rigid transverse supporting member. The spring employed is preferably of helical shape, such as is commonly used at the ends of a bed spring of this character, and is so disposed that its longitudinal axis has a substantial vertical component.

Referring now in detail to the drawing, 10 is a bed spring of the type with which my invention may be employed and comprises a flat horizontal upper mattress supporting surface 11 formed from a metallic fabric, such as for example the links shown in Figs. 1 and 3. If desired, any other type of well known metallic fabric, such as for example, wire mesh or cable spring, may be employed to form the said surface 11 without departing from the spirit of my invention.

The supporting frame comprises a pair of elongated rigid members 12 which may take the form of hollow oval-shaped tubes adapted to be supported in the usual sockets provided for this purpose on a bed frame. The longitudinal members 12 are interconnected by means of cast brackets 13 having socket portions 14 in which the ends of the hollow members 12 are received and permanently fixed. Extending angularly upward from each socket 14 is a leg portion 15 having firmly attached to its upper end, as by means of rivets 16, an L-shaped channel member 17 which joins opposite brackets 13.

The ends of the metallic fabric comprising the top surface 11 of the spring are attached to the horizontal legs 17a of the channels 17 by means of a plurality of close-coiled, parallelly disposed, helical springs 18, said springs having one set of ends disposed in the loops 19 of the link fabric and the other ends in apertures 20 provided in the horizontal leg 17a.

When mounting the supporting surface 11, the springs 18 are tensioned in the usual manner so as to maintain the metallic fabric 11 under tension longitudinally of the bed spring.

It will be observed that up to this point I have described a bed spring which is characteristic of the type under consideration, and it will be apparent as the description proceeds that other springs of this general nature may be employed with my invention.

To the longitudinal side edges of the metallic fabric 11 I attach, as by means of a plurality of wire clips 21, a rigid rail 22 of the same general L-shape as the channel member 17, the horizontal leg 22a of the said rail being in substantially the same plane as the horizontal leg 17a of the metallic fabric 11. The ends of the rails 22 are resiliently supported from the horizontal channel members 17 in the same manner as the ends of the metallic fabric 11, by close-coiled, helical springs 23 which are similarly tensioned between the legs 17a and the ends of the side rails 22.

In accordance with my invention I provide a highly simplified means for resiliently suspending the rigid longitudinal rails 22 from the transverse channels 17 in such manner as to prevent undue sagging of the side edges of the bed spring. Such means comprises an extension projecting outwardly and downwardly from both ends of the rails 22 and having a portion which is generally below and substantially under the horizontal leg 17a of the channel 17.

In the preferred form of my invention, said extension comprises a flat strip 24 having a pair of angularly disposed legs 25 and 26, one of which 25 is juxtaposed and riveted to the vertical leg 22b of a rail 22 adjacent an end thereof. The other leg 26 is suspended from the horizontal leg portion 17a by a helical spring 27 whose longitudinal axis has a substantial vertical component, as may be clearly seen in Figs. 2 and 5. The upper end of said spring is attached to the leg 17a by means of a hook 28 passing through an aperture 29 in the said leg, and the lower end of said spring 27 is attached by a similar hook 30 to the leg 26 passing through an aperture 31 at the end thereof.

Similar springs 27 are provided on each end of both rigid rails 22. It will be seen that in this manner the rigid rails which define the longitudinal side edges of the bed spring are resiliently suspended in an exceedingly simple manner from the rigid transverse supports at the head and foot of the said bed spring; so that when a weight is applied to the side edge of the metallic fabric 11, as by a person sitting on the edge of a bed, this weight will be distributed and assimilated between and by the substantially vertically disposed helical springs 27, which suspend the rail 22 on which the person is sitting. As soon as the weight is removed the rails 22 will be immediately resiliently urged back to their normal position with the horizontal leg 22a lying in the plane of the metallic fabric 11.

If desired, instead of providing a separate extension member 24 attached to the side rail 22, I may, as shown in the modified form of my invention illustrated in Fig. 6, bend the two ends of the said rail 22. This may be accomplished by cutting out a V notch in the vertical leg 22b of the rail 22 and then bending the horizontal leg 22a of said rail until the two edges of the notch meet, as indicated at 35. These edges may then be welded and a hole 36, similar to the hole 31, provided at the end of the rail to receive the hook 30 of the vertical coil spring 27, as shown in the first form of my invention.

It will thus be seen that there is provided a device in which the several objects of this inven-

tion are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a bed spring having a flat horizontal mattress supporting surface comprising a metallic fabric, rigid supporting members for the head and foot ends of said fabric, said members being disposed in the plane of said fabric and means interconnecting said fabric and said members to resiliently tension said fabric between said members, the combination of a pair of rigid rails attached to the side edges of said fabric and defining the longitudinal edges of said spring, said rails having a horizontal web substantially in the plane of said metallic fabric, means to interconnect said rails adjacent the ends thereof to said supporting members to resiliently tension said rails between said supporting members, and means to resiliently suspend said rails from said supporting members, the portions of said rails with which said suspension means is associated being disposed below the plane of said fabric.

2. In a bed spring having a flat horizontal mattress supporting surface comprising a metallic fabric, rigid supporting members for the head and foot ends of said fabric, said members being disposed in the plane of said fabric and means interconnecting said fabric and said members to resiliently tension said fabric between said members, the combination of a pair of rigid rails attached to the side edges of said fabric and defining the longitudinal edges of said spring, said rails having a horizontal web substantially in the plane of said metallic fabric, means to interconnect said rails adjacent the ends thereof to said supporting members to resiliently tension said rails between said supporting members, and means to resiliently suspend said rails from said supporting members, said last named means comprising a spring so disposed as to have a substantial vertical component, the portions of said rails with which said suspension means is associated being disposed below the plane of said fabric.

3. In a bed spring having a flat horizontal mattress supporting surface comprising a metallic fabric, rigid supporting members for the head and foot ends of said fabric, said members being disposed in the plane of said fabric and means interconnecting said fabric and said members to resiliently tension said fabric between said members, the combination of a pair of rigid rails attached to the side edges of said fabric and defining the longitudinal edges of said spring, said rails having a horizontal web substantially in the plane of said metallic fabric, horizontally disposed means to interconnect said rails adjacent the ends thereof to said supporting members to resiliently tension said rails between said supporting members, the ends of said rails being disposed substantially below the plane of said fabric, and means to resiliently suspend said rails from said supporting members, said means including a spring interconnecting the end of said rail to said supporting

member, said spring being so disposed as to have a substantial vertical component.

4. In a bed spring having a flat horizontal mattress supporting surface comprising a metallic fabric, rigid supporting members for the head and foot ends of said fabric, said members being disposed in the plane of said fabric and means interconnecting said fabric and said members to resiliently tension said fabric between said members, the combination of a pair of rigid rails attached to the side edges of said metallic fabric and defining the longitudinal edges of said bed spring, said rails having a horizontal web substantially in the plane of said metallic fabric and disposed between said head and foot end supporting members, means to interconnect said rails adjacent the ends thereof to said supporting members to resiliently tension said rails between said supporting members, an extension member rigidly attached to each of the ends

5 of said rails, the free end of said extension members being disposed substantially under said supporting members, and a spring interconnecting said supporting members and the free end of each of said extension members.

10 5. In a bed spring as set forth in claim 1, wherein the portions of said rails with which said suspension means is associated are the ends of the rails and wherein said means for resiliently tensioning said rails between said supporting member is horizontally disposed, suspension means for each end of each of the rails consisting of a spring so disposed as to have a substantial vertical component, the upper end of said spring depending from the supporting member at the head or foot of the spring, the end of said rail being hung from the other end of said spring.

MORRIS TUCKER.
